COMBINED WASHING AND DRYING MACHINE

Jerry N. Lewis, 3129 Daniels, Dallas, Tex.

Filed Nov. 18, 1959, Ser. No. 58,381

Term of patent 7 years

(Cl. D49—1)

FIG. 1 is a top perspective view of a combined washing and drying machine, embodying my new design;

FIG. 2 is a bottom plan view thereof;

FIG. 3 is an elevational view thereof.

I claim:

The ornamental design for a combined washing and drying machine, as shown.
